H. Percy Bentley
ATTORNEY.

UNITED STATES PATENT OFFICE.

ARTHUR ROBINSON HEGGAN, OF DOVER, DELAWARE.

PUMP BLEEDER.

Application filed January 21, 1928 Serial No. 248,439.

This invention relates to pump bleeders for use in connection with lift pumps, and is designed primarily to release the volume of water contained in the casing of a lift pump, whereby the column of water in the pump casing above the frost line may be released when desired; but it is to be understood that a pump bleeder in accordance with this invention may be used for releasing other liquids for which it is found applicable.

The invention has for its objects to provide in a manner hereinafter set forth, a pump bleeder for the purposes referred to, within convenient reach, which is self-aligning in its operation, and which will not injure the hands by catching them between the handle and pump casing. Further objects of the invention are to provide a stopper in combination therewith, the contour of which will compensate for the arc of the operating lever, and which when seated within the casing is capable of maintaining a water-tight joint, without independent tensioning devices, regardless of the vibrations of the pump.

Further objects of the invention are to provide, in a manner hereinafter set forth, a pump bleeder for the purposes referred to, which is simple in its construction and arrangement of parts, strong, durable, compact, thoroughly efficient in its use, readily installed, easily repaired, and comparatively inexpensive to set up.

With the foregoing and other objects in view the invention consists of the novel construction, combination and arrangement of parts as hereinafter more specifically described and illustrated in the accompanying drawings, wherein is shown an embodiment of the invention, but it is to be understood that changes, variations and modification can be resorted to which fall within the scope of the claims hereunto appended.

In the drawings wherein like reference characters denote corresponding parts throughout the several views:

Fig. 1 is a fragmentary view in side elevation of a pump casing showing the adaptation therewith of the pump bleeder in accordance with this invention; and further, with a cutaway portion of the pump casing in the area of the stopper.

Fig. 2 is a fragmentary view in front elevation of a pump casing showing the adaptation therewith of the pump bleeder in accordance with this invention.

A pump bleeder in accordance with this

invention includes an angular operating lever L which is pivotally attached to the front face of a pump casing 2 by a U-shaped bracket B. The bight 3 of the pivot bracket is spaced with respect to the front of the pump casing 2 and is circular in cross-section. The sides of the bracket B are flared and flattened as at 4, so as to provide a plane surface to conform to the side faces of the pump casing 2. The flared section 4 is perforated in its center line to receive screws 5, by means of which, it is secured to the side faces of the pump casing.

The pivoted operating lever L is substantially circular in cross-section and is angular shaped in contour with respect to its length. When the lower section 6 of the operating lever is in a valve seated position as shown in Fig. 1, it is disposed in spaced parallel relation with respect to the front face of the pump; whereas the handle section 1, while in a valve seated position, is angularly disposed therefrom. At a point where the two sections 1 and 6 of the operating lever form the obtuse angle, said sections are flared and flattened to a substantially circular section 7. The flared area 7 is perforated in close proximity to the center thereof, as at 8, to receive the pivot support 3, upon which it swings.

Near the lower end, the operating lever is enclosed within a U-shaped guide member G, which provides perfect alignment during the swinging motion. The guide member G is made of a strip of metal rectangular in cross-section having bases 10, vertical sides 11, and a bight 13. The laterally extending bases 10 of the guide bracket conform to the front face of the pump casing, and the faces thereof are perforated in a center line to receive screws 12, by means of which the guide bracket is secured to the pump casing. The perpendicularly extending sides 11, of the guide bracket, are in spaced parallel relation with respect to each other, providing by the spaced inner faces thereof a vertical guide for the operating lever. The outer ends of the sides 11 are closed at 13 to prevent the operating lever from swinging out of alignment and to space the outer end of the handle portion 1 from the pump casing when the valve is entirely open.

The lower end of the operating lever terminates in a flattened circular portion 14 which is perforated at its center to receive a screw 15 by means of which the resilient frustoconical shaped stopper 16 is secured to the operating lever. The sides 17 and 18 of the stopper 16, which taper from the inner to the

outer end thereof, compensate for the circular swinging path of the operating lever, or any imperfections residing in the walls of the seat, and provides a water-tight joint when 5 positioned within the opening 19 of the pump casing.

What I claim is:

1. In combination, a pump casing having an opening; a U-shaped bracket having its extremities straddling the pump casing and provided with a straight bight portion disposed in spaced parallelism with the side of the casing having said opening; a resilient stopper of frusto-conical contour for insertion in 10 said opening to close the same; a lever having an intermediate flat portion provided with an opening through which projects said bight portion for pivotally mounting said lever; said stopper secured to the end of one 15 arm of the lever, the other arm of the lever being angularly disposed relative to the first mentioned arm to diverge from said side of the casing when the stopper is in the said opening; and a U-shaped guide member having 20 outwardly disposed bases on its extremities fixed to said side of the casing so that the sides of the member extend from the side of the casing perpendicularly, one on each side of the lever, and the bight of the guide member 25 being spaced from said side of the casing so as to prevent the extremity of said angularly disposed arm of the lever from striking the casing when the lever abuts said bight portion of the guide member.
- 35 2. In combination, a pump casing having an opening; a U-shaped bracket having its extremities straddling the pump casing and

provided with a straight bight portion disposed in spaced relation to the side of the casing having said opening; a stopper for insertion within the opening to close the same; a lever of angular contour with respect to its length with an opening at the angle through which projects said bight portion for pivotally mounting the lever; means for mounting the stopper on one end of the lever; and a U-shaped guide member fixed to said side of the casing with the sides of the member extending perpendicularly from the side of the casing in spaced parallel relation to each other and tangent to the lever, and the bight of the guide member being spaced from the side of the casing to prevent the other end of the lever from striking the casing when said lever abuts said bight portion of the guide member. 45 50 55

3. In combination, a pump casing having an opening; a U-shaped bracket having its extremities straddling the pump casing and provided with a straight bight portion; a stopper for insertion within the opening to close the same; a lever of angular contour with respect to its length pivotally mounted at the angle upon said bight portion; means for mounting the stopper on the end of one arm of the lever; and a U-shaped guide member fixed to the side of the pump casing, said guide having spaced sides extending perpendicularly from the said side and tangent to the lever, and said guide member provided with a bight portion spaced from the side of the casing to prevent the end of the other arm of the lever from striking the casing. 60 65 70

In testimony whereof I affix my signature.
ARTHUR ROBINSON HEGGAN.
